UNITED STATES PATENT OFFICE

153,672

DESIGN FOR A HIGH CHAIR

Rocco Di Giorgio, Franklin Park, Ill.

Application August 13, 1947, Serial No. 140,840

Term of patent 3½ years

(Cl. D15—1)

To all whom it may concern:

Be it known that I, Rocco Di Giorgio, a citizen of the United States, residing in Franklin Park, in the county of Cook and State of Illinois, have invented a new, original, and ornamental Design for a High Chair, of which the following is a specification, reference being had to the accompanying drawing, forming a part thereof.

In the drawing:

Figure 1 is a front perspective view of a high chair embodying my new design;

Figure 2 is a perspective view showing the front and one side of a high chair embodying my new design, the opposite side of the chair being the same in appearance as the side shown in this view; and

Figure 3 is a perspective view showing one side and the rear of a high chair embodying my new design.

I claim:

The ornamental design for a high chair, as shown and described.

ROCCO DI GIORGIO.
